MACHINE FOR OPERATING ON SHOES OR
SHOE PARTS

Erastus E. Winkley, Lynn, Mass., assignor to
United Shoe Machinery Corporation, Borough
of Flemington, N. J., a corporation of New Jersey

Application November 10, 1938, Serial No. 239,846

45 Claims. (Cl. 12—17)

This invention relates to machines for operating on shoes or shoe parts and is herein illustrated and described as embodied in a shank reducing machine.

5 It is an object of this invention to provide an improved feeding arrangement in a machine for operating on shoes or shoe parts. In accordance with a feature of the invention the illustrated machine is provided with a plurality of gages for determining the position of the work piece 10 relatively to an operating tool, in combination with means actuated by the gages to effect a relative movement between the work piece and the tool to cause the tool to perform an operation upon the work piece when all of the gages 15 have been engaged by the work piece. In the illustrated machine each of the gages has a connection to a clutch mechanism, which connections are constructed and arranged to prevent the clutch mechanism from starting a feeding 20 movement until all the gages are pressed against by the work piece. As illustrated, each of the gages is mounted for a limited yielding movement under pressure of the work piece and the control means connected to the gage is operated 25 by such movement of the gage resulting from the pressure of the work piece. The feed control mechanism comprises a pair of clutch members normally latched out of engagement with each other and urged into engaging position by 30 a resilient means, the movement of the gages operating to unlatch the clutch members and thereby to start the feeding movement.

It has been found convenient in the illustrated 35 machine to arrange certain of the above-mentioned gages in such a manner that after determining the initial position of the work piece they would, unless moved, remain in the path of feed of the work piece. In accordance with another 40 feature of the invention means are provided for removing the gages from the path of feed, such means being operated automatically by the feeding mechanism at the beginning of the feeding cycle.

45 It is a further object of the invention to provide a convenient arrangement for adjusting the machine for operations not only upon work pieces of different sizes but also of different styles. In accordance with this object a feature 50 of the invention consists in the provision of a

lever connected to a gage to control the position thereof, in combination with means for adjusting the position of the lever about its fulcrum and with means for adjusting the position of the fulcrum. One of these adjustments serves 5 to position the gage for operations in accordance with the size of the work pieces, and the other in accordance with the style. The illustrated machine is provided with a scale graduated to indicate sizes and a pointer constructed and arranged for manual movement over the range of 10 graduations of the scale and having connections to the gage for controlling the position the position of the gage, the machine being further provided with mechanism operable upon said connections for varying the relation between the 15 pointer and the gage to enable the gage to be adjusted for work of a desired style.

A still further object of the invention is to provide a machine wherein the direction of the 20 feeding movement is reversible for better operation upon articles which come in rights and lefts, such as soles. In accordance with this object the illustrated machine is provided with an arrangement for reversing the direction of the 25 feeding movement of a sole support and with cutting means adapted to operate on soles fed in both directions. The reversible feeding mechanism is driven in one direction from a source of external power and in the reverse direction by a spring. The cutting means consists of a 30 pair of knives having their cutting edges disposed to operate upon a sole fed in opposite directions in combination with means for moving each of the knives between operative and out-of-the-way position according to the direction of 35 relative feeding movement.

In accordance with still another feature of the invention a pair of oppositely disposed gages are provided for gaging a sole successively from 40 the same end to present opposite lateral margins of the sole to an operating means, in combination with means for feeding the sole successively in opposite directions. Means are provided for adjusting these gages toward and from each 45 other in accordance with the size of the soles to be operated on and in addition means are provided for adjusting the gages asymmetrically with respect to the operating means in accordance with the styles of work to be performed. 50

With the above and other objects and features in view the invention will now be described with reference to the accompanying drawings and pointed out in the claims.

5 In the drawings,

Fig. 1 is a front elevation of the improved machine;

Fig. 2 is a side elevation of the machine;

10 Fig. 3 is a plan view of the end portion of the machine;

Fig. 4 is a section on line IV—IV of Fig. 2;

Fig. 5 is a section on the line V—V of Fig. 2;

Fig. 6 is a section on the line VI—VI of Fig. 2;

Fig. 7 is a section on the line VII—VII of Fig. 2;

15 Fig. 8 is a section on the line VIII—VIII of Fig. 2; and

Fig. 9 is a section on the line IX—IX of Fig. 2.

In the shank reducing machine herein illustrated, a sole is supported upon a work table 10 in 20 the position indicated by the reference character S (Fig. 3). The toe end of the sole is pressed against a gage 12, the edge of the forepart of the sole is pressed against a gage 14, and the edge of the heel portion of the sole is pressed against a 25 gage 16. When all three gages are thus engaged by the sole, automatic mechanism later to be described will cause rotation of a lower feed wheel 18 and an upper feed wheel 20. The lower feed wheel 18 operates through a notch in the work table 10.

30 As soon as the feeding movement begins the gage 12 is lowered out of the path of movement of the sole and a shank reducing knife 22 makes a reducing cut in the lateral margin of the sole which terminates when the feeding movement ceases,

35 the extent of the feeding movement being adjustable. The sole is then replaced upon the table 10 in reversed position as indicated by the reference character S' (Fig. 3) with the toe end against a gage 24, the edge at the forepart being against

40 the gage 14 and the edge at the heel portion being held against a gage 26. The pressure of the sole against these three gages again starts a feeding movement of the sole, this time in a reverse direction, to cause the sole to be operated upon by

45 a second shank reducing knife 28 (Figs. 1 and 2) disposed in a direction appropriate to the direction of feed of the sole. This knife 28, it should be noted, was in an out-of-the-way position while the work piece was being fed in operative

50 relation to the knife 22, the knife 22 being removed from operative position and the knife 28 being moved into operative position by mechanism which later will be described.

55 The supporting structure of the machine comprises several upright frame members 30 (Fig. 2) extending from a base 32 adapted to be secured upon a work bench. The first and second frame members 30, from the forward end of the machine, are reinforced by a bridge 31 (Fig. 3) connecting their upper portions. The work table 10 has two rearwardly extending lugs 33 which are secured by screws 35 to the forward frame member 30. Pivotally mounted for heightwise movement about a pin 331 (Fig. 2) secured in one of

60 the rearward frame members 30 is a head 34. The pin 331 engages a slot 36 formed in the head 34 to provide for longitudinal adjustment of the latter, such adjustment being effected by a screw 38 (Figs. 2 and 3) threaded into another of the

65 frame members 30 and having a smooth shank portion which turns in an open-ended slot formed slot formed in a lug 40 on the head 34. A collar 42 and a head 44 on the screw 38 engage opposite sides of the lug 40 to move the latter as the screw

70 is turned. A pair of bearing surfaces 46 (Figs.

2 and 6) formed on the head 34 are slidably engageable with the corresponding surfaces formed on upstanding portions 48 of the frame member 30 to guide the head in its rising and falling movement about the pin 331. An operating rod 50 (Figs. 2 and 6) which is slidably keyed to the bridge 31 has a horizontal slot 52 (Fig. 2) formed in its upper end to engage a pin 54 extending from the head 34. A compression spring 56 surrounding the rod 50 and interposed between the lower surface of the base 32 and a nut 58 threaded on the rod 50 tends to hold the head 34 down in a stop position which is determined by a screw 60 threaded into the frame 30 and having a head 62 engageable with an under surface formed on the head 34. The head 34 may be raised in opposition to the spring 56 by a lever 64 (Fig. 6) which is fulcrumed upon a pin 66 secured in the frame 30 and which has a forked end 68 which engages a collar 70 adjustably secured upon the operating rod 50. The lever 64 is operated through a rod 72 the lower end of which is connected to a treadle (not shown). The feed wheel 20, the knives 22 and 28 and the forepart edge gage 14 are all carried by the head 34 and rise and fall in accordance with variations in the thickness of soles being operated upon.

Journalized in the frame 30 is a main shaft 74 (Figs. 2 and 6 to 9, inclusive). Secured upon the shaft 74 is a cam 76 (Figs. 2 and 7) having a peripheral face which, in the illustrated machine, is eccentric with respect to the shaft 74 and which is engaged by a roll 78. A lever 80 having a hub 81 whereby the lever is fulcrumed upon a pin 82 fixed in the frame 30 carries the cam roll 78 at one of its ends and at its opposite end is pivotally connected to one end of a link 84 the opposite end of the link 84 being pivotally connected to an arm 86 extending from a sleeve 88 which, in turn, is mounted for free rotation upon the shaft 74. A longitudinal slot 90 formed in the lever 80 enables a shouldered pin 92 which constitutes the pivotal connection between the lever 80 and the link 84 to be adjusted at any desired radial distance from the axis of the fulcrum 82. Surrounding the hub 81 is a torsion spring 94 which tends to rotate the lever 80 in a counterclockwise direction, as seen in Fig. 7, thereby holding the cam roll 78 at all times in engagement with the cam 76. The outer end portion of the arm 86 extends over a considerable arc about the axis of the shaft 74 and constitutes a gear segment 96 which is in mesh with a pinion 98 secured upon a shaft 100 which is journaled in the head 34. The outer end of the shaft 100 carries the upper feed wheel 20. The lower feed wheel 18 is mounted upon the outer end of a shaft 102 journaled in the frame 30 and movement of the lower feed wheel is transmitted from the upper feed wheel shaft through a pair of gears 104 and 106 secured upon their respective shafts.

Mechanism which will later be described is provided for driving the shaft 74 through a half revolution and then automatically stopping. It is evident from an inspection of Fig. 7 that a half turn of the shaft 74 will cause the cam roll 78 to move from its extreme position toward the right to its extreme position toward the left, causing movement of the lever 80 in a clockwise direction thereby rocking the gear segment 96 in a clockwise direction (as viewed in Fig. 7) and rotating the shaft 100 and the upper feed wheel 20 in a counter-clockwise direction (as viewed in Figs. 7 and 1) and causing the lower feed wheel to be rotated correspondingly in the opposite direction.

The next half turn of the shaft 74 will enable the spring 94 to move the lever 80 and the parts connected therewith in the opposite direction while the cam roll 78 rides upon the surface of the cam 76. It is apparent, therefore, that during one cycle of operation the feed rolls will operate to feed a work piece in one direction and during the next cycle they will operate to feed in the opposite direction. The length of the feeding movement is determined by adjustment of the pin 92 toward or from the axis of the fulcrum 82. The outline of the cam 76, which in the illustrated machine is circular and eccentric with respect to the shaft 74, will result in a feeding movement which accelerates rapidly from zero velocity at the beginning and decelerates rapidly to zero velocity at the end, the actual travel of the work piece being practically negligible during the periods of rapid acceleration and deceleration.

The shaft 74 as above mentioned is driven by a mechanism actuated by the pressure of a sole against the various gages. When a half revolution has been completed the movement stops automatically. The mechanism for thus driving the shaft 74 derives its movement from a pulley 108 (Figs. 2 and 9) loosely mounted on the shaft 74 and driven from any suitable source of power in the direction indicated by the arrow in Fig. 9. Extending from the pulley 108 is a sleeve or hub 110 which carries a cam disk 112, the periphery of which is engaged by a cam roll 114. The greater portion of the periphery of the disk 112 is circular and concentric with the axis of the shaft 74; there are, however, two diametrically opposite raised portions 116 and 118. The roll 114 is mounted for free rotation upon the end of an arm 120 which is pivotally mounted upon a pin 122 secured in an extension 124 of one of the frame members 30. The arm 120 is urged downwardly by a spring 126 which tends to maintain the roll 114 in engagement with the peripheral surface of the cam disk 112. Fulcrumed upon a pin 128 secured in the frame 30 close to the base 32 is an arm 130 the upper end portion of which is beveled, as indicated by the reference numeral 132 (Fig. 2). Slidably keyed upon the shaft 74 is a clutch member 134 having a disk 136 from one face of which extend two raised portions 138 which are diametrically opposite each other and which are beveled to correspond to the beveled surface 132. The disk 136 carries four clutch pins 140 which are parallel to and arranged concentrically around the shaft 74. Raised from the end face of the cam 112 is a disk 142 having four openings 144 which may be engaged by the pins 140, the leading edges of the openings being beveled as indicated by the reference numeral 145 in Fig. 2. A compression spring 146 constantly urges the clutch member 134 toward the right, as viewed in Fig. 2, urging the pins 140 to a position of engagement with the openings 144 and thereby causing the drive of the pulley 108 to be transmitted through the clutch member 134 to the shaft 74. The upper end of the arm 130 is normally interposed between the disks 136 and 144 with the beveled surface 132 against one of the corresponding beveled surfaces of the raised portions 118, thereby holding the clutch member 134 in open or disengaged position against the force of the spring 146.

Integral with the arm 130 and extending angularly therefrom is an arm 148 having an end portion 150 which is notched to form a shelf 152. Three depending latches 154, 156 and 158 are

pivotedly mounted in side-by-side relation upon a pin 160 secured in an upright portion 162 of the frame, each of which latches has a notch formed in its lower end which is engageable with the shelf 152 to prevent upward movement of the arm 148. A tension spring 164 which is weaker than the spring 126 is interposed between the arm 148 and the arm 120 tending to rock the arm 130 in a clockwise direction, as viewed in Fig. 9. The tendency of the spring 164 to rock the arm 130, however, is normally overcome by the three latches 154, 156 and 158, any one of which is sufficient to hold the arm 148 down as long as its notched end engages the shelf 152. Pivotedly connected to the arm 148 is the lower end of a link 166 in the upper end portion of which is formed a slot 168. Extending laterally from the arm 120 is a pin 170 engaging the slot 168. The length of the link 166 is such as to bring the bottom of the slot 168 substantially into engagement with the pin 170 when the arm 120 is in its low or normal position with the roll 114 on the circular portion of the cam 112 and with the arm 148 occupying its normal latched position as shown in Fig. 9. Pivotedly connected to the arms 154, 156 and 158 are links 172, 174 and 176, respectively. These links are connected to the various gage members in a manner later to be explained and operate to disconnect the latches 154, 156 and 158 when the sole or work piece is held against the gages.

Assuming now that the various gages are thus engaged by a work piece and that the three arms or latches 154, 156 and 158 have all been disengaged from the shelf 152, the tension of the spring 164 will tend to rock the arm 130 from the position in which it is shown in Figs. 9 and 2. Nothing can happen, however, while the arm 120 is in its low or normal position because the pin 170 exerts through the link 166 a downward thrust derived from the spring 126 which is more than enough to overcome the upward pull of the spring 164 on the arm 148. As soon as the rise 118 of the rotating cam 112 raises the arm 120 the spring 164 will raise the arm 148, rocking the arm 130 in a clockwise direction, as seen in Fig. 9. The upper end of the arm 130 is thereby removed from between the disks 136 and 144, and the spring 146 will urge the clutch member 134 toward the right into engaging position until end bearing 50 surfaces 178 on the raised portions 138 engage the face of the disk 142. The pins 140 will engage the openings 144 as soon as the latter come into register with the pins and the rotation of the shaft 74 will begin. The continued rotation of the cam disk 112 will first bring the rise 118 away from the roll 144, enabling the arm 120 to drop to its normal position. The arm 130, however, will be prevented from swinging in a counter-clockwise direction by a bearing surface formed on the inside upper portion of the arm 130 and engaging the periphery of the raised portion 138. Continued rotation of the clutch disk 136 will bring the raised portion 138 away from the upper end of the arm 130 which thereupon will swing into the space between the disks 136 and 144 and occupy its normal position as shown in Figs. 2 and 9. Still further rotation of the disk 136 will bring the beveled surface of the other raised portion 138 into engagement with the bevel 132 of the arm 130, thereby wedging the clutch member 134 to the left (as viewed in Fig. 2) and disengaging the clutch. The latches 154, 156 and 158, which will have engaged the shelf 152 as soon as the arm 130 swings into normal posi-

75 Three depending latches 154, 156 and 158 are

tion, will now serve to hold the arm 130 in normal position until the latches are again disengaged by the pressure of another work piece against the gages.

5 The knives 22 and 28, as has already been mentioned, are mounted for movement into and out of operative position to enable each knife to be suitably disposed in relation to the direction of feed of the work piece. To this end the knives 10 are both carried upon a bracket 180 (Figs. 1 and 2) which is fulcrumed for free pivotal movement about the upper feed wheel shaft 100. The knife 22 has a rearwardly extending rectangular shank which is secured by a set screw 182 in a block 183 15 having a cylindrical stem which passes through alined openings in two spaced ears depending from a block 184. A clamping member 185 occupies the space between the above-mentioned ears and has an opening to accommodate the cylindrical stem of the block 183. The member 185 20 has a rearwardly extending stem upon which is threaded a nut. When this nut is tightened against the adjacent rear surfaces of the depending ears it will draw the clamping member rearwardly and bind the cylindrical stem of the block 183 securely to the block 184. A clamping screw 186 extending through a longitudinal slot 188 in the block 184 adjustably secures the latter to the bracket 180. An adjusting screw 190 having a 25 head suitably grooved for engagement with a flange extending from the block 184 is threaded through a lug 192 on the bracket 180. Upon loosening the clamping screw 186 the block 184 may be adjusted longitudinally to provide a 30 heightwise adjustment for the knife 22 by turning the screw 190. The knife 28 is similarly mounted by a block 191, a clamping member 193, and a set screw 194 to a block 196. A clamping screw 198 extending through a longitudinal slot 40 200 secures the block 196 to the bracket 180. An adjusting screw 202 having a head suitably grooved to engage a flange extending from the block 196 is threaded through a lug 204 extending from the bracket 180. Turning of the screw 45 202 after the clamping screw 198 has been loosened serves to adjust the block 196 longitudinally and thereby to adjust the knife 28 to a desired heightwise operating position.

Mechanism for swinging the bracket 180 about the axis of the shaft 100 to bring one or the other of the knives into operating position comprises a link 206 pivotally connected at one end to the upper portion of the bracket 180 and pivotally connected at its other end to an eccentric pin carried by a disk 208. Journaled in bearings 210 formed in the head 34 is a shaft 212 upon the forward end of which is secured the disk 208 and upon the rearward end of which is secured a gear 214 (Figs. 1, 2 and 8). Meshing with the gear 60 214 is a gear segment 216 formed upon an arm 218 of a bell crank member which is fulcrumed upon a pin 220 secured in an upwardly extending portion 222 of the frame 30. The above-mentioned bell crank has another arm 224 which is 65 pivotally connected to the upper end of a link 226 the lower end of which is connected to an arm 228 of a second bell crank. This second-mentioned bell crank is fulcrumed upon a pin 230 secured in the frame portion 222 and has a downwardly extending arm 232 which carries a cam roll 234. Secured upon the main shaft 74 is a cam 236 having a concentric peripheral cam surface 238 of relatively large radius extending through an arc of nearly 180° and a concentric 70 peripheral surface 240 of relatively small radius

diametrically opposite the surface 238 and also extending over nearly 180°. A pair of non-radial surfaces 242 and 244 connect the surfaces 238 and 240 and render the entire periphery of the cam 236 continuous. The roll 234 is held against the periphery of the cam 236 by a spring 241 which urges the arm 232 toward the left as viewed in Fig. 8. The cam 236 is so arranged upon the shaft 74 that at the beginning of each cycle of movement the cam roll 234 will travel along one or the other of the inclined surfaces 242 or 244 thereby suddenly rocking or enabling the spring 241 to rock the bell crank 232, 228 between its two extreme positions and thereby moving one of the knives into its operating position while simultaneously moving the other knife to an out-of-the-way position. While the knives are performing these movements the feed of the work piece will be so slight, owing to the design and arrangement of the cam 16, as to be negligible. 20

The gage 14 (Figs. 1, 2 and 3) for the edge of the forepart of the sole has a rearwardly extending shank 246 having a tongue 248 by which it is slidably guided for forward and rearward movement in a groove formed in the bracket 180. 25 A screw 252 threaded in the bracket 180 and having a shouldered head engaging a slot in the shank 246 retains the tongue 248 in its guide groove. The rearward end of the shank 246 engages a plate 256 formed on the upper portion of a lever 258 (Figs. 2, 3 and 6) which, in turn, is fulcrumed upon a pin 260 extending laterally from one of the frame members 30. The lower end of the lever 258 is pivotally connected to the forward end of the link 174 which, as has 30 already been explained, is one of the three links controlling the clutch mechanism. A tension spring 261 (Figs. 2 and 8) secured to the link 174 and anchored to a lateral extension of one of the frame members 30 urges the link 174 35 rearwardly into latching position and urges the upper portion of the lever 258 forwardly or to the left as seen in Fig. 2. When a sole is pressed against the gage 14 the pressure of the sole against the gage 14 will rock the lever 258 in a 40 clockwise direction, as viewed in Fig. 2, and thereby operate to disconnect one of the three latches which hold the clutch mechanism in inoperative position. The screw 252 by engagement with the ends of its slot in the shank 24 limits the 45 movement of the gage 14 both forwardly and rearwardly.

Provision is made for moving the toe gages 12 and 24 and the heel edge gages 16 and 26 downwardly out of the path of the advancing sole as soon as the feeding movement begins. This is accomplished by supporting these gages upon mechanism comprising a pair of upper parallel arms 262 (Figs. 1, 2, 3, 6, 7 and 8) and 55 264 and a pair of lower arms 266 and 268 which 60 are parallel to each other and also to the arms 262 and 264. All four of these parallel arms are fulcrumed at their rearward ends for heightwise swinging movement upon pins 265 secured in lateral extensions of one of the rearward frame 65 members 30. The lower arms 266 and 268 have inward extensions 271 (Fig. 6) having bearing surfaces which are in sliding engagement with bearing surfaces 273 on the frame member 30 to 70 guide the arms. All four arms are pivotally secured at their forward ends by pins 267 to lugs 269 extending rearwardly from a bracket 270 which carries the toe gages and the heel edge gages. It is evident that by reason of this arrangement the bracket 270 may rise and fall 75

without tilting and without otherwise substantially changing its position. The rising and falling movement of the bracket 270 is controlled through a bell crank 272 (Figs. 2, 3 and 6) fulcrumed upon a pin 274 secured in the frame 30. One arm of the bell crank 272 carries a roll 216 which engages a slot 278 formed in the upper arm 262. The other arm of the bell crank 272 extends downwardly and carries a cam roll 280 which engages a cam face 282 formed on a disk 284 which, in turn, is secured upon the cam shaft 74. The weight of the arms 262, 264, 266 and 268, together with the parts carried thereby, holds the roll 280 against the cam face 282. The cam face 282 has a raised portion 286 which at the beginning and end of a cycle, that is, whenever the cam shaft 74 is stationary, engages the cam roll 280 to hold the bell crank 272 in the position shown in Fig. 2 with the gage carrier arms raised. As soon as the shaft 74 begins to rotate, the roll 280 will drop from the raised portion 286, enabling the gage carrier bracket 270 to drop and lower the gages out of the path of feeding movement of the work piece.

The heel edge gages 16 and 26 consist of arcuate plates having straight work-engaging edges and secured by clamping screws 287 (Fig. 3) upon brackets 288 and 290, respectively, said brackets being fixed upon the opposite ends of a transversely extending shaft 292 (Fig. 6) which is journaled in bearings 294 formed on the upper rearward extensions 269 of the bracket 270. A slot 293 (Fig. 2) is formed in the forward frame member 30 to accommodate the up-and-down movement of the shaft 292. The clamping screws 287 pass through arcuate slots 289 in the gages to provide for securing the gages in any desired position of angular adjustment, the centers about which the arcs of the slots are taken lying in the straight work-engaging edges. Extending downwardly from the shaft 292 is an arm 296 the lower end of which is pivotally connected to the link 176. A spring 297 (Figs. 2 and 8) urges the link 176 rearwardly to latching position and also urges the gages 16 and 26 forwardly. It is evident that the pressure of a sole against either of the gages 16 and 26 will rock the shaft 292 and will cause the link 176 to unlatch one of the three latches which hold the clutch in inoperative position. A stop lug 301 (Fig. 2) extending rearwardly from the bracket 270 and engageable with the lower end portion of the arm 296 limits the rearward movements of the heel edge gages under pressure of the work pieces.

The toe gages 12 and 24, as has already been mentioned, are carried by the heightwise movable bracket 270 and are supported by an adjusting mechanism which is directly mounted upon the bracket 270 by a pair of pins 298 (Fig. 1) and 300. This mechanism comprises a pair of parallel arms 302 and 304 having their lower ends pivotally mounted upon the pins 298 and 300, respectively. The upper ends of the arms 302 and 304 are pivotally connected to a link 306 at points which lie in a line parallel to a line connecting the centers of the pins 298 and 300. Pivotally connected to the arms 304 and 302 between and in parallel relation to the link 306 and the line joining the centers of the pins 300 and 298 is a bar 308 which carries a pair of fulcrum pins 310 and 312. Fulcrumed upon the pin 310 is a bell crank comprising an arm 314 and an arm 316. A similar bell crank comprising an arm 318 and an arm 320 is fulcrumed upon the pin 312. A pair of levers 322 and 324 which

normally occupy positions in line with each other are also fulcrumed upon the pins 310 and 312, respectively. Upon the outer end of the lever 322 is pivotally mounted an upstanding link 326, the upper end of which carries a fulcrum pin 328 of a bell crank comprising a pair of arms 330 and 332. The arm 330 is pivotally connected to the upper end of the arm 316, being parallel to the lever 322 while the link 326 is parallel to the arm 316. Upon the upper end of the arm 332 is a plate which constitutes the toe gage 24. On the outer end of the lever 324 is pivotally mounted an upstanding link 334 the upper end of which carries a pin 336 which constitutes a fulcrum for a bell crank comprising a pair of arms 338 and 340. The link 334 is parallel to the arm 320 and the arm 338 is parallel to the lever 324. Formed upon the upper end of the arm 340 is a plate which constitutes the toe gage 12. Interposed between a lug 342 upon the bar 308 and the under surface of an extension 344 on the link 326 is a compression spring 346. A screw 348 passing loosely through an opening in the lug 342 and threaded into the extension 344 adjustably limits the degree of separation which the spring 346 is able to effect between the lug 342 and the extension 344. A similar lug 350 extending from the opposite end of the rod 308 constitutes an abutment for one end of a compression spring 352, the opposite end of which bears against the under surface of an extension 354 of the link 334. A screw 356 passing loosely through an opening in the lug 350 and threaded into the extension 354 adjustably limits the degree of separation which can be effected by the spring 352 between the lug 350 and the extension 354.

Threaded upwardly through the free inner ends of the levers 322 and 324 respectively are abutment screws 500 and 502. A plate 504 (Fig. 40) having an under surface which is engageable by the upper ends of the screws 500 and 502 is carried upon the free forward end of an arm 506 which is fulcrumed upon a horizontal pin 507 mounted in the bracket 270. The arm 506 has a tail 508 which extends rearwardly through an opening in the bracket 270 and then downwardly, and which is connected at its lower end to the forward end of the link 172. A tension spring 510 (Figs. 2 and 8) urges the link 172 rearwardly to a latching position.

The operation of the toe gages as so far described will now be explained. The arms 320 and 316 are stationary for any given setting of an adjusting mechanism later to be described. Assuming now that the toe end of a sole is pressed against one of the toe gages, for example the gage 12, the result will be a rotation of the bell crank 340, 338 about its pivotal connection to the stationary arm 320. The spring 352 will yield under the downward thrust of the link 334 and the lever 324 will rotate in a counter-clockwise direction, as viewed in Fig. 1, always remaining parallel to the arm 338. The extent of actual movement of the gage 12 will be slight, being limited by the maximum compression of the short spring 352. The movement of the lever 324 will bring the screw 502 into engagement with the plate 504, causing the tail 508 to pull the link 172 forwardly to release one of the three latches which hold the clutch disengaged. The same result will be accomplished by pressing a sole against the other toe gage 24, in which case the movement will be transmitted through the screw 500 to the plate 504.

The mechanism for adjusting the toe gages for soles of different sizes and styles will now be described. Pivotedly mounted upon the pin 300 is a sleeve 358 from which an arm 360 extends upwardly. The upper end portion of the rod 360 constitutes a pointer 362 and is provided with a knob 364 to facilitate swinging the arm 360 about the pin 300. Secured upon the forward edge of the work table 10 is an arcuate plate 366 upon which are formed graduation marks to indicate adjustments of the pointer 362 for various sizes of soles to be operated upon. Extending from the sleeve 358 is another arm 368 the outer end portion of which is pivotally connected to and constitutes one of the supports for an upright member 370 the intermediate portion of which is laterally offset to avoid interfering with other portions of the mechanism. The upper portion of the member 370 is pivotally connected to one end of an arm 372, the other end of which arm is pivotally supported upon a pin 374 secured in the bracket 270. It is evident that by reason of this arrangement swinging movement of the pointer 362 will cause the arm 368 to raise or lower the member 370 while the arm 372 will always maintain the member 370 in substantially upright position. Pivotally mounted upon and depending from an elongated pin 373 secured in the upper end of the member 370 is an arm 376 upon the lower portion of which is formed a pointer 378. Carried upon a forward extension 379 of the lower end of the member 370 is a plate 380 upon which are formed scale markings to indicate various style adjustments for the pointer 372. Formed in the lower portion of the arm 376 is a closed longitudinal slot 382 within which is slidably mounted a block 384. Threaded through the block 384 is a screw 386 having a knurled head 388 and a collar 390 spaced from the head. A bracket 392 which is pivotally mounted upon a pin which constitutes the pivotal connection between the arm 368 and the member 370 has an upstanding lug 394 which engages the smooth shank of the screw 386 between the collar 390 and the head 388 to prevent endwise movement of the screw. It is evident that turning of the head 388 will adjust the pointer 378 in relation to the scale graduations on the plate 380. It will be noted that these scale graduations extend from each side of a zero mark which lies in the line joining the centers of the pin connecting the arm 368 to the member 370 and the pin connecting the arm 376 to the member 370. These style adjustments, as will be explained later, will be of the same magnitude for right and left shoes but will be on opposite sides of the zero mark. Accordingly, the pointer 378 can be shifted for right and left shoes merely by the operator grasping a knob 396 extending from the block 384 and rotating the bracket 392 in a clockwise direction, as viewed in Fig. 1, until the block 384 engages the lower end of the slot 382, causing the position of the pointer to be reversed in relation to the zero mark.

The connections for controlling the position of the gages 12 and 24 by means of the pointers 362 and 378 comprise a bracket 398 (Fig. 2) secured by two screws 400 (Fig. 1) to the inner surface of the arm 376. The inner end of the bracket 398 slidably engages a vertical guideway formed by a pair of parallel flanges 402 formed on a plate 404 (Fig. 5) which is rigidly secured upon the link 306. Confined between the arm 376 and the inner portion of the bracket 398 are a pair of

coaxial cylindrical swivel blocks 406 and 408 each having an end face bearing against the other. Bearing pins 410 and 412 extending from the opposite end faces of the blocks 406 and 408, respectively, and journaled in suitable openings in the arm 376 and the bracket 398 serve to center the pins for rotary movement independently of each other. The blocks 406 and 408 are diametrically bored for sliding engagement with a pair of rods 414 and 416 respectively, the rods 414 and 416 being extensions of the bell crank arms 318 and 314 respectively. 5 10 15

The operation of the toe gage adjusting mechanism will now be described. The setting of the pointer 362 for size adjustments will raise or lower the member 370 bodily and with it the arm 376 carrying the bracket 398. The two bell crank arm extensions 400 and 402 will thus simultaneously be rocked in opposite directions about their respective fulcras, causing the arms 316 and 320 likewise to rock the toe gages simultaneously in opposite directions about their respective fulcras. Thus, for a large size sole, the pointer 362 will be swung to the left, as seen in Fig. 1, causing a relative separation of the toe gages. This adjustment, it will be observed, will be effective regardless of the position of the style pointer 378. Having adjusted the toe gages for size the operator then proceeds to turn the knurled head 388 to adjust the pointer 378 to a desired style. Such movement of the arm 376 will operate through the bracket 398 to swing the link 306 to the right or left, as the case may be, thereby swinging the arms 302 and 304 in the same direction and shifting the toe gages 12 and 24 through their supporting mechanism bodily and in unison to the right or to the left. The pointers 362 and 378 are in sufficient frictional engagement with their respective scale plates to hold the mechanism in adjusted position even when a sole is pressed against either of the gages 12 and 24 with a force sufficient to operate the driving clutch. 20 25 30 35 40

In the operation of the machine a sole is placed upon the work table 10 and introduced between the feed wheels 18 and 20 in the position indicated 45 by the reference character S (Fig. 3) with the toe end of the sole against the gage 12, the edge of the sole in the vicinity of the ball line against the gage 14 and with the edge at the heel end against the gage 16. The sole chosen for purposes 50 of illustration is an outsole intended for the right foot, the tread or grain surface of the sole resting upon the work table and the flesh surface being uppermost. When the sole has been pressed against the three gages above mentioned 55 they will yield slightly and, when they have yielded to their limiting positions, will gage the sole accurately in relation to the knife 22, it being important that the beginning of the cut to be made by the knife 22 be accurately gaged from 60 the toe end of the sole. As soon as all three gages have yielded under the pressure of the sole against them the feeding mechanism will begin to advance the sole in the direction of the heel end and the knife 22 will make a shank reducing cut from the 65 position indicated in Fig. 3 and terminating at the end of the feeding movement the extent of which is determined by the adjustment of the pin 92 in the slot 90 (Fig. 7). However, the exact point at which the cut terminates is unimportant and 70 the operator may release the sole by hand when, in his judgment, a sufficient length of cut has been made. It should be noted that at the beginning of the feeding movement and before the sole has been advanced any appreciable distance 75

- the gages 12 and 16 are automatically lowered out of the path of travel of the sole. The sole may now be replaced in reversed position upon the work table 10, as indicated by the reference 5 character S' with the toe end of the sole against the gage 24, the edge of the sole in the vicinity of the ball line against the gage 14 and with the edge of the sole at the heel end in engagement with the gage 26. The operation is now repeated 10 to form a shank reducing cut upon the opposite lateral margin of the same sole. The cut this time will be made by the knife 28 which will have been automatically swung into operating position at the beginning of the feeding movement. The 15 operator now swings the knob 396 (Fig. 1) toward the right, reversing the pointer 378 to adjust the gage mechanism for left soles and proceeds in the manner outlined above to present the corresponding left sole to the machine.
- 20 Having thus described my invention, what I claim as new and desire to secure by Letters Patent of the United States is:
1. In a machine for operating on shoe parts, an operating tool, a plurality of gages adapted to be pressed against by a work piece to control the position of the work piece relatively to said tool, and means actuated by said gages to effect a relative movement between the work piece and the tool to cause the tool to perform an operation 25 upon the work piece only when all of the gages have been engaged by the work piece.
  2. In a machine for operating on shoe parts, an operating tool, a plurality of gages adapted to be pressed against simultaneously by a work piece 30 to control the position of a work piece relatively to said tool, and means actuated by said gages to initiate a relative feeding movement between the work piece and the tool only when all of the gages have been engaged by the work piece.
  3. In a machine for operating on shoe parts, an operating tool, normally inoperative means for effecting relative movement between a work piece and said operating tool to cause the tool to perform an operation upon the work piece, a plurality of gages engageable with a work piece 35 at various localities of the work piece to determine the position of the work piece relatively to said operating tool, said gages being mounted for yielding movement when engaged by the work piece, and means operated by said gages to render said normally inoperative means operative to effect said relative movement between the work piece and the tool only upon movement of all of said gages by engagement with the work piece.
  4. In a machine for operating on shoe parts, an operating tool, normally inoperative means for effecting a relative feeding movement between a work piece and said operating tool, a plurality of gages simultaneously engageable with a work piece 40 at various localities of the work piece to determine the position of the work piece relatively to said operating tool, said gages being mounted for yielding movement when engaged by the work piece, and means operated by said gages to render said normally inoperative means operative to effect relative feeding movement between the work piece and the tool only upon movement of all of said gages by engagement with the work piece.
  5. In a machine for operating on shoe parts, an operating tool, means for effecting a relative feeding movement between a work piece and said operating tool, a clutch mechanism in said movement effecting means for starting and stopping 45
- the feeding movement, a plurality of gages for determining the position of the work piece relatively to said operating tool, said gages being mounted for yielding movement when engaged by the work piece, and a connection from each 5 of said gages to said clutch mechanism, said connections being constructed and arranged to prevent said clutch mechanism from starting the feeding movement until all of said gages have been moved by being pressed against by the 10 work piece.
6. A sole fitting machine comprising a stationary knife for operating upon a sole, mechanism for feeding a sole in operative relation to said knife, a gage mounted for yielding movement 15 under pressure of the sole, a stop for limiting the movement of said gage to enable said gage to control the position relatively to said knife of a sole pressed against the gage, and control means connected to said gage for starting said feeding 20 mechanism upon yielding movement of the gage resulting from the pressure of the sole.
7. A sole fitting machine comprising a stationary knife for operating upon a sole, mechanism for feeding a sole in operative relation to said knife, a pair of clutch members in said feeding mechanism for controlling the starting and the stopping of the feeding movement, resilient means tending to couple said clutch 25 members to start the feeding movement, a latch mechanism normally holding said clutch members apart, a gage mounted for yielding movement when pressed against by the sole, a stop for limiting the movement of said gage to enable said 30 gage to control the position relatively to said knife of a sole pressed against the gage, and means operated by said gage in yielding under the pressure of a sole for tripping said latch mechanism to enable the clutch members to couple and thereby start the feed of the sole. 35
8. A sole fitting machine, comprising a stationary knife for operating upon a sole, a driven feed wheel for feeding and supporting the sole in operative relation to the knife, means for holding the sole against said feed wheel, means for driving said feed wheel, a normally disengaged clutch mechanism through which said driving means may operate to drive said feed wheel, a gage for determining the position of the sole 40 relatively to said knife, said gage being mounted for limited yielding movement when pressed against by the sole, and means operated by said gage when a sole is pressed thereagainst for engaging said clutch mechanism to start the drive 45 of the feed wheel.
9. A sole fitting machine, comprising a stationary knife for operating upon a sole, means for feeding the sole in operative relation to said knife, a clutch mechanism including a latch, 50 said clutch mechanism being constructed and arranged to start the operation of said feeding means when and not until the latch is tripped, a gage mounted for yielding movement when pressed against by the sole, a stop for limiting the movement of said gage to enable said gage to control the position relatively to said knife of a sole pressed against the gage and means operated by said gage when the sole is pressed against the 55 gage for tripping said latch.
10. A sole fitting machine comprising a stationary knife for operating upon a sole, normally inoperative means for feeding the sole in operative relation to said knife, a toe gage for the sole, an edge gage engageable with the forepart 70
- 75

- of the sole, an edge gage engageable with the heel portion of the sole, each of said gages being mounted for limited yielding movement under pressure of the sole, and means controlled by 5 said gages for starting the operation of said feeding means when and not until all of said gages have been pressed against by the sole.
11. In a machine for operating on shoe parts, operating means, normally inoperative means for 10 feeding a work piece past said operating means, a bell crank, a fulcrum for said bell crank, a gage upon one of the arms of said bell crank for determining the initial position of the work piece, means operable upon the other arm of said bell 15 crank for adjusting said gage about said fulcrum, and means operated by said fulcrum upon the pressure of a work piece against said gage for starting the operation of said feeding means.
12. In a machine for operating on shoe parts, 20 operating means, normally inoperative means for feeding a work piece past said operating means, a bell crank, a fulcrum for said bell crank, a yieldable support for said fulcrum, a gage upon one of the arms of said bell crank for determining 25 the initial position of the work piece, means pivotally connected to the other arm of said bell crank for adjusting said gage about said fulcrum, and means operated by said fulcrum in yielding when a work piece is pressed against said gage 30 for starting the operation of said feeding means.
13. In a machine for operating on shoe parts, a gage against which a work piece may be held to determine the position of the work piece at the beginning of a feeding movement, means for 35 feeding the work piece beyond the position determined by said gage, a support for said gage positioned away from said feeding means, and means operated by said feeding means for removing said gage from the path of feed of the 40 work piece.
14. In a machine for operating on shoe parts, a gage against which a work piece may be held to determine the position of the work piece at the beginning of a feeding movement, means for 45 feeding the work piece beyond the position determined by said gage, a cam operated by said feeding means, and means controlled by said cam for normally maintaining said gage in operative position and for removing the gage 50 from the path of feed of the work upon the beginning of a work-feeding movement.
15. In a sole fitting machine, cutting means adapted for operation upon soles, a support for maintaining a sole in operative engagement with 55 said cutting means, and means for moving said support to feed a sole relatively to said cutting means, said moving means being constructed and arranged for reversal of the direction of feeding movement, and said cutting means being constructed and arranged for operation upon work 60 fed in both directions.
16. In a sole fitting machine, cutting means, a support for a sole, a reversible mechanism for effecting a relative feeding movement between 65 said cutting means and said sole support to cause the cutting means to operate on the sole, power-driven means for causing said feeding mechanism to effect a relative feeding movement in one direction, and a spring for causing the feeding mechanism to effect a relative feeding movement in the opposite direction.
17. A machine for performing a stock-fitting 70 operation upon soles, comprising means for feeding soles in opposite directions, a knife having a cutting edge disposed to operate upon a sole 75 fed in one of said directions, a second knife having a cutting edge disposed to operate upon a sole fed in the opposite direction, and means for moving each of said knives between operating and out-of-the-way positions, said knife-moving means being constructed and arranged to move each knife to its out-of-the-way position when the other knife is moved to its operative position.
18. A machine for performing a stock-fitting 10 operation upon soles, comprising a sole-feeding mechanism constructed and arranged to perform feeding movements alternately in opposite directions, a pair of knives having cutting edges oppositely disposed for operation according to the direction in which a sole is being fed, and means 15 operated by said feeding mechanism for moving each of said knives into an operating position when the sole is fed in a direction appropriate to the disposition of the cutting edge of that knife and for simultaneously moving the other 20 knife into an out-of-the-way position.
19. In a machine for operating on shoe parts, operating means, a gage for positioning a work piece relatively to said operating means, a relatively stationary scale graduated to indicate 25 sizes, a pointed constructed and arranged for manual movement over the range of graduations of said scale, a lever connected to said gage, a fulcrum for said lever, a connection between said pointer and said lever for controlling the position of the gage in accordance with the pointer, and means for adjusting the position of said fulcrum to modify the size adjustment of said gage in accordance with a desired style.
20. In a machine for operating on shoe parts, 30 operating means, a gage for positioning a work piece relatively to said operating means, a lever connected to said gage for controlling the position thereof, a fulcrum for said lever, means for adjusting the position of said lever about said 35 fulcrum, and means for adjusting the position of said fulcrum, one of said adjusting means serving to adjust the gage for operations according to size and the other adjusting means serving to adjust the gage for operations according to 40 style.
21. In a sole fitting machine, means for operating upon a lateral margin of a sole, a pair of gages oppositely disposed in relation to said operating means for gaging a sole successively 45 from the same end to present opposite lateral margins of the sole to said operating means, and means for feeding the sole successively in opposite directions.
22. In a sole fitting machine, means for operating upon a lateral margin of a sole, a pair of gages oppositely disposed in relation to said operating means for gaging a sole successively 50 from the same end to present opposite lateral margins of the sole to said operating means, means for feeding the sole successively in opposite directions, and control means operated by said gages and constructed and arranged to prevent the operation of said feeding means until a sole has been pressed against either of said 55 gages.
23. In a sole fitting machine, means for operating upon a lateral margin of a sole, a pair of gages oppositely disposed in relation to said operating means for gaging a sole successively 60 from the same end to present opposite lateral margins of the sole to said operating means, a bell crank one arm of which is connected to one of said gages, a second bell crank one arm of which is connected to the other of said gages, 65

and means engageable with the free arms of said bell cranks for swinging said bell cranks in opposite directions to adjust the distance between said gages for the purpose of insuring that 5 the operations will be performed at corresponding localities on soles of various sizes.

24. In a sole fitting machine, means for operating upon a lateral margin of a sole, a pair of gages oppositely disposed in relation to said 10 operating means for gaging a sole successively from the same end to present opposite lateral margins of the sole to said operating means, a bell crank one arm of which is connected to one of said gages, a swivel block having a diametrical bore through which the other arm of said bell crank is freely slideable, a second bell crank one arm of which is connected to the other of 15 said gages, a second swivel block having a diametrical bore through which the second-mentioned bell crank is freely slideable, a common carrier on which said swivel blocks are rotatably mounted to accommodate the swinging movements of said bell cranks, and means for varying the position of said carrier to swing said bell 20 cranks simultaneously in opposite directions to adjust the distance between said gages for the purpose of insuring that the operations will be performed at corresponding localities on soles of various sizes.

25. In a sole fitting machine, means for operating upon a lateral margin of a sole, a pair of gages oppositely disposed in relation to said operating means for gaging a sole successively from 30 the same end to present opposite lateral margins of the sole to said operating means, and means for adjusting said gages asymmetrically with respect to said operating means to cause the operation upon one lateral margin to take place at a greater or less distance from an end of a sole than the operation upon the other lateral margin in accordance with the style of work to be performed.

26. In a sole fitting machine, means for operating upon a lateral margin of a sole, a pair of gages oppositely disposed in relation to said 45 operating means for gaging a sole successively from the same end to present opposite lateral margins of the sole to said operating means, a link, connections between said gages and said link, and means for shifting said link to adjust said gages asymmetrically with respect to said operating means to cause the operation upon one lateral margin to take place at a greater or less distance from an end of the sole than the operation upon the other lateral margin.

27. In a sole fitting machine, means for operating upon a lateral margin of a sole, a pair of gages oppositely disposed in relation to said 50 operating means for gaging a sole successively from the same end to present opposite lateral margins of the sole to said operating means, a link connected to each of said gages, and an adjusting screw connected to said link for varying unequally the distances of said gages from said operating means, thereby causing the operation upon one lateral margin to take place at a greater or less distance from an end of the sole than the operation upon the other lateral margin.

28. In a sole fitting machine, means for operating upon a lateral margin of a sole, a pair of gages oppositely disposed in relation to said 55 operating means for gaging a sole successively from the same end to present opposite lateral margins of the sole to said operating means, a

common means for adjusting said gages toward and from each other to cause the operations to be performed at corresponding localities on soles of various sizes, and a common means for adjusting said gages asymmetrically with relation 5 to the operating means to cause the operation upon one lateral margin of a sole to take place at a greater or less distance from the end of that sole than the operation upon the other lateral margin.

29. In a sole fitting machine, means for operating upon a lateral margin of a sole, a pair of gages oppositely disposed in relation to said operating means for gaging a sole successively from the same end to present opposite lateral margins 10 of the sole to said operating means, a lever connected to each of said gages for controlling the position thereof, a fulcrum for each of said levers, means for adjusting said levers about their fulcras, and means for adjusting the positions of said fulcras, one of said adjusting means serving to adjust the gages for operations according to size and the other adjusting means serving to adjust the gages according to style.

30. In a sole fitting machine, means for operating upon a lateral margin of a sole, a pair of gages oppositely disposed in relation to said operating means for gaging a sole successively from the same end to present opposite lateral margins 15 of the sole to said operating means, a lever connected to each of said gages for controlling the position thereof, a fulcrum for each of said levers, a common support for said fulcras, means for adjusting said levers angularly about their fulcras to vary the distance between said gages in accordance with the sizes of the soles to be operated upon, and means for varying the position of said fulcras support to adjust said gages asymmetrically with reference to said operating 20 means in accordance with the style of work to be performed.

31. In a sole fitting machine, means for operating upon a lateral margin of a sole, a pair of gages oppositely disposed in relation to said operating means for gaging a sole successively from the same end to present opposite lateral margins 25 of the sole to said operating means, a pair of bell-crank levers, one of said bell-crank levers having an arm connected to one of said gages and the other bell-crank lever having an arm connected to the other of said gages, a fulcrum for each of said bell-crank levers, a link connecting said fulcras, an adjusting member, a connection for transmitting longitudinal movement to said link from said adjusting member to adjust said gages asymmetrically with respect to said operating means in accordance with the style of work to be performed, and swivel connections upon said adjusting member having sliding engagement with the other arms of said bell-crank levers to rock the bell-crank levers upon movement of the adjusting member transversely of said link and thereby to adjust the gages toward and from each other in accordance with 30 the sizes of soles to be operated upon.

32. In a sole fitting machine, means for operating upon a lateral margin of a sole, a pair of gages oppositely disposed in relation to said operating means for gaging a sole successively from the same end to present opposite lateral margins 35 of the sole to said operating means, means for adjusting said gages asymmetrically with respect to said operating means to cause the operation upon one lateral margin to take place at a greater 40

or less distance from an end of a sole than the 5
operation upon the other lateral margin in accordance with the style of work to be performed, and means for reversing the asymmetric adjustment of said gages to cause the operations to take place at corresponding localities on right and left soles.

33. In a sole fitting machine, means for operating upon a lateral margin of a sole, a pair of 10
gages oppositely disposed in relation to said operating means for gaging a sole successively from the same end to present opposite lateral margins of the sole to said operating means, a common 15
means for adjusting said gages asymmetrically with respect to said operating means to vary the distance from an end of a sole of the localities at which the operations take place on the opposite lateral margins of the sole, and a common 20
means for reversing such adjustment by shifting each of said gages to a locality equal in distance from the operating means to the locality formerly occupied by the other gage, thereby adapting the machine to operations upon right and left soles.

34. In a machine for operating upon the lateral 25
margins of soles, operating means, a pair of gages oppositely disposed in relation to and at unequal distances from said operating means for gaging a sole from an end thereof to cause the operation to be performed upon one lateral margin of 30
the sole at a greater or less distance from an end of the sole than upon the other lateral margin, and a common means for shifting each of said gages to a locality equal in distance from the operating means to that formerly occupied by the other gage, thereby adapting the machine to operations upon right and left soles.

35. In a machine for operating upon the lateral margins of soles, operating means, a pair of gages oppositely disposed in relation to and at unequal 40
distances from said operating means for gaging a sole from an end thereof to cause the operation to be performed upon one lateral margin of the sole at a greater or less distance from an end of the sole than upon the other lateral margin, a link 45
connecting said gages, an arm pivotally mounted for swinging movement, and a connection between said arm and said link for shifting said gages simultaneously upon a swinging movement of said link.

36. In a machine for operating upon the lateral margins of soles, operating means, a pair of gages oppositely disposed in relation to and at unequal 50
distances from said operating means for gaging a sole from an end thereof to cause the operation to be performed upon one lateral margin of the sole at a greater or less distance from an end of the sole than upon the other lateral margin, a link 55
connecting said gages, an arm pivotally mounted for swinging movement, a connection between said arm and said link for shifting said gages simultaneously upon swinging movement of said arm, and an adjusting member pivotally mounted for swinging movement, said arm having a longitudinal slot engageable by said adjusting member to transmit movement from said adjusting member to said arm, and said adjusting member being constructed and arranged to swing said arm from one side to the other of the pivotal mounting 60
of said adjusting member to reverse the inequality of the distances of said gages from said operating means.

37. In a machine for operating upon the lateral margins of soles, operating means, a pair of gages 70
oppositely disposed in relation to and at unequal 75
distances from said operating means for gaging a sole from an end thereof to cause the operation to be performed upon one lateral margin of the sole at a greater or less distance from an end of the sole than upon the other lateral margin, a link 5
connecting said gages, an arm pivotally mounted for swinging movement, a connection between said arm and said link for shifting said gages simultaneously upon swinging movement of said arm, an adjusting member pivotally mounted for swinging movement, said arm having a longitudinal slot engageable by said adjusting member to transmit movement from said adjusting member to said arm, said adjusting member being constructed and arranged to swing said arm from one side to the other of the pivotal mounting of said adjusting member to reverse the inequality of the distances of said gages from said operating means, and means for varying the effective length of said adjusting member to vary said inequality. 20

38. In a machine for operating upon shoe parts, operating means, a pair of gages for positioning a work piece relatively to said operating means, a link connecting said gages, an arm pivotally mounted for swinging movement, and a connection between said arm and said link for shifting said gages simultaneously upon a swinging movement of said arm. 25

39. In a machine for operating upon the opposite lateral margins of soles, operating means, a gage engageable with an end of a sole to position the sole relatively to said operating means, an operator-controlled member constructed and arranged for movement between two limiting positions, and a connection between said member and said gage for locating the gage in accordance with the position of the member whereby the gage may be located in one position for an operation upon the inner lateral margin of one of a pair of soles and in a different position for an operation upon the outer lateral margin of the other sole of said pair. 30

40. In a machine for operating upon the opposite lateral margins of soles, operating means, a gage engageable with an end of a sole to position the sole relatively to said operating means, an arm having a longitudinal slot formed therein, a connection between said gage and said arm for locating the gage in accordance with the position of the arm, and a lever pivotally mounted at one end and having its free end engaging the slot of said arm, said lever being adapted to be swung about its pivot by the operator to swing said arm between two limiting positions, one of which determines the adjustment of the gage for the inner lateral margin of one of a pair of soles and the other of which determines said adjustment for the outer lateral margin of the other sole of said pair. 40

41. In a machine for operating upon soles, operating means, a gage for positioning a sole relatively to said operating means, an arm having a longitudinal slot formed therein, a connection between said gage and said arm for locating the gage in accordance with the position of the arm, an operator-controlled extensible lever pivotally mounted for swinging movement and engaging said slot to control the position of said arm and therefore of said gage in accordance with the effective length of the lever and also in accordance with the position of the lever about its pivotal mounting. 50

42. In a machine for use in the manufacture of shoe parts, an operating tool, a plurality of 55
70
75

gages for controlling the position of a work piece relatively to said tool, said gages being mounted for yielding movement when engaged by the work piece, and means operated by said gages to effect a relative movement between the work piece and the tool to cause the tool to perform an operation upon the work piece when all the gages have been moved by the work piece.

5 43. In a sole fitting machine, cutting means, and means for effecting a relative movement between a sole and said cutting means to cause the cutting means to operate upon the sole, the direction of said relative movement being along the edge of the sole, said movement-effecting means being constructed and arranged for reversal of the direction of relative movement and said cutting means being constructed and arranged to operate upon relative movement in each direction.

10 44. In a sole fitting machine, cutting means, means for effecting a relative feeding movement between a sole and said cutting means to cause the cutting means to operate progressively upon the sole, the direction of said relative feeding

movement being along the edge of the sole, said movement-effecting means being constructed and arranged for reversal of the direction of relative feeding movement, and a gage engageable with the edge of the sole for determining the relative 5 operating positions of the sole and the cutting means.

15 45. In a sole fitting machine, a pair of cooperating driven rolls engageable with the opposite surfaces of a sole to feed a sole in reverse directions along the edge thereof, a knife, a second knife, a carrier for said knives, and means for moving said carrier between two operating positions, in one of which positions the first-mentioned knife is positioned to operate upon a 15 sole fed in one direction and the second-mentioned knife is in an out-of-the-way position, and in the other of which positions of said carrier the second-mentioned knife is positioned to operate on a sole fed in the reverse direction and 20 the first-mentioned knife is in an out-of-the-way position.

ERASTUS E. WINKLEY.
